Specification for Design.

Patented Sept. 10, 1918.

Application filed April 11, 1916. Serial No. 90,515. Term of patent 14 years.

To all whom it may concern:

Be it known that I, ELIZABETH B. CLAPP, a citizen of the United States, residing at Boston, county of Suffolk, State of Massachusetts, have invented a new, original, and ornamental Design for Tooth-Brushes, of which the following is a specification, reference being had to the accompanying drawing, forming part thereof.

Figure 1 of the drawings is a perspective view of a tooth brush embodying my improved ornamental design;

Fig. 2 is a side view thereof;

Fig. 3 is an end view looking toward the right in Fig. 2;

Fig. 4 is an end view looking toward the left in Fig. 2.

I claim:

The ornamental design for a tooth brush, as shown.

ELIZABETH B. CLAPP.
